131,792

DESIGN FOR AN ELECTRIC FOOD MIXER

Hermann M. Alfred Strauss, Chicago, Ill.

Application May 20, 1939, Serial No. 85,099

Term of patent 14 years

To all whom it may concern:

Be it known that I, Hermann M. Alfred Strauss, a citizen of the United States, residing at Chicago, in the county of Cook and State of Illinois, have invented a new, original, and ornamental Design for Electric Food Mixers, of which the following is a specification, reference being had to the accompanying drawing, forming a part thereof.

Fig. 1 is a side elevational view of an electric food mixer, showing my design;

Fig. 2 is a top plan view; and

Fig. 3 is a front elevational view thereof.

I claim:

The ornamental design for an electric food mixer, as shown.

HERMANN M. ALFRED STRAUSS.
